United States Patent Office

Des. 225,688
Patented Dec. 26, 1972

225,688

EYEGLASSES

Mary Irene Wick, 7533 Parkdale, Clayton, Mo. 63105

Filed May 19, 1971, Ser. No. 145,108

Term of patent 14 years

Int. Cl. D16—06

U.S. Cl. D57—1

FIG. 1

FIG. 2

FIG. 3

FIG. 4

FIG. 1 is a front elevational view of eyeglasses showing my new design;

FIG. 2 is a top view thereof;

FIG. 3 is a right side view thereof, the side opposite to that shown being similar in appearance; and

FIG. 4 is a bottom view thereof.

I claim:

The ornamental design for eyeglasses, substantially as shown and described.
